Patented June 27, 1916.

INVENTOR:
G. A. Madison
BY his ATTORNEY:
A. M. Larsen.

UNITED STATES PATENT OFFICE.

GEORGE A. MADISON, OF ST. PAUL, MINNESOTA.

SOAP-CARRIER AND MASSAGE DEVICE.

1,188,668.

Specification of Letters Patent. Patented June 27, 1916.

Application filed August 30, 1915. Serial No. 47,985.

To all whom it may concern:

Be it known that I, GEORGE A. MADISON, a citizen of the United States, residing at St. Paul, in the county of Ramsey and State of Minnesota, have invented a new and useful Soap-Carrier and Massage Device, of which the following is a specification.

My invention relates to combined soap carrying and massaging devices, and the main object is to provide a massaging device adapted to contain and conceal a cake of soap and to be carried in a pocket for the ready and private use of travelers and other persons. This and other objects I attain by the novel construction and combination illustrated in the accompanying drawing, in which—

Figure 1 is a front view of the device unfolded and containing a cake of soap. Fig. 2 is a section on the line *a—a* in Fig. 1. Fig. 3 is a longitudinal section of the device showing how it is operated by a hand 6, shown in dotted lines. Fig. 4 is an end view of the device containing a cake of soap and fully folded up ready to be carried in a garment pocket or other suitable container.

Referring to the drawing by reference numerals, 1 designates a cake of soap carried in a soft rubber pouch 2, which by a forwardly open extension 3 is integrally connected with a slightly larger pouch 4 which is also of soft rubber and upon more or less of its inner surface it is provided with massaging teeth or studs 5, 5^a; the teeth 5 having concave ends and those marked 5^a having convex ends.

When the device is to be carried in the pocket or otherwise placed away, the soap is placed in the small pouch 2 and said pouch is then pushed into the larger pouch 4, as shown in Fig. 4. And when the device and soap are to be used the device is opened as in Fig. 1, the soap removed, the pouch 4 turned inside out and placed upon the hand 6 as in Fig. 2, while the small pouch 2 may either extend loosely along the hand, as 2^b in

Fig. 3, or it may be pushed into the pouch 4 as shown at 2^a in Fig. 3, where it is pressed flat under the fingers 7 of the hand, while it is obvious that if so desired the fingers 50 may be passed into it. The soap together with water may now be applied to hands, face or other parts of the body and the device applied like a combined bath brush and massaging brush, applying the convex teeth 55 for ordinary use and the concave teeth for the special massaging by which it is desired to draw the blood to the surface. After the device is thus used and rinsed it is restored to the normal position shown in Fig. 4, with the soap within it, and after wiping it outside with the towel it is ready to be carried in the pocket until next time it is wanted.

It is useless to illustrate the teeth 5, 5^a upon every part of the body of the device 65 where they might be provided, since that would be only a matter of degree, it being evident that such teeth may be provided upon more or less of the inner surface or even the outer surface of the device.

What I claim is:

1. A soap holder adapted to be carried in a garment pocket and comprising a flexible body formed with two pouches one smaller than the other and designed to contain a cake of soap and to be inserted into the larger pouch, one of said pouches being designed as a massage mitten and provided with series of massaging teeth or studs.

2. A soap holder adapted to be carried in a garment pocket, the same comprising a flexible body formed with a large pouch and a small pouch adapted to contain a cake of soap and to be inserted into the larger pouch, said larger pouch having its inner side provided with massaging teeth or studs and so flexible as to be reversed inside out to bring the teeth into position for use during the massaging process.

In testimony whereof I affix my signature.

GEORGE A. MADISON.
